VOLTAGE DIVIDER

Ronald V. Tetz, Los Gatos, Calif., assignor to Jennings
Radio Manufacturing Corporation, San Jose, Calif., a
corporation of Delaware

Filed Dec. 26, 1962, Ser. No. 72,958

Term of patent 14 years

(Cl. D26—1)

FIG. 1 is a top perspective view of a voltage divider, showing my new design; and

FIG. 2 is a bottom perspective view thereof.

A portion of each figure is stippled to indicate contrast in appearance.

I claim:

The ornamental design for a voltage divider, as shown and described.
